TOY PERCUSSION GUN

Harry J. Criner, Davenport, Iowa, assignor of one-half to A. G. Bush, Davenport, Iowa

Application December 28, 1946, Serial No. 718,925

3 Claims. (Cl. 46—191)

1

My invention relates to toy guns in which a spring-operated drawbar is used to drive a carrier ring slidably mounted upon the barrel to propel a projectile carried by the carrier ring.

The objects of my invention are to provide a toy gun which may be operated by a manually actuated crank or by a trigger and which will drive a ring projectile or a tubular slide along the barrel; to provide means by which the tubular slide, after being fired, will be automatically returned to its charged position in the carrier; to provide such a gun which will act as a repeater when operated by the crank and will simulate the sound and action of a machine gun. Other objects will appear from the description.

I accomplish these objects by the means illustrated in the accompanying drawings, in which:

Figure 1 is a longitudinal section on the line 1—1 of Figure 2;

Figure 2 is a longitudinal section on the line 2—2 of Figure 1;

Figure 3 is a cross-section on the line 3—3 of Figure 2;

Figure 4 is a sectional detail on the line 4—4 of Figure 5; Figure 5 is a sectional detail of an alternate form of the line 5—5 of Figure 4.

Similar numerals refer to similar parts throughout the several views.

My gun comprises a stock 1 which may be of wood, plastic or metal as desired, and may be formed by shaping, casting, stamping or other means.

The front end of the stock is extended to form a seat for the barrel 4 which may be secured to the stock by any suitable means, such as a pin or bolt 4—1.

A chamber 1—1 is formed in the front extension of the stock 1—a.

A shaft 9 is revolvably mounted in the sides of the extension of the stock and has a crank 12 united to one end thereof with a handle 11 secured to the outer end of the crank by which it can be turned. The opposite end of the shaft 9 has a head formed thereon or may be secured by a suitable nut or other holding device.

The middle of the shaft 9 has united thereto a yoke 10 which revolves with the shaft 9 and the outer end of which is arranged to engage the rear end of a flexible drawbar 13, the front end of which is engaged by a hook 15 formed upon the end of a tension spring 14 the front end of which is secured in the barrel by a hook 16 engaging a pin 7.

The middle of the drawbar is provided with a pin 17 which extends through the barrel and

2

is slidable in slots 5 and 6 formed in the barrel. The outer ends of the pin 17 are firmly seated in a cylindrical carrier 18 slidably mounted upon the barrel 4 and so arranged that as the crank 12 is revolved in the direction shown by the arrow in Figure 2, the yoke 10 will engage the upturned rear end of the drawbar 13 and carry the drawbar downward and backward until the drawbar comes into engagement with the shaft 9 when the yoke will be detached from the rear end of the drawbar and the drawbar will be rapidly drawn forward by the tension spring 14 carrying with it the carrier 18.

A tubular slide 20, which may be attractively colored, is mounted upon the barrel and made of a size to permit it to slide into an enlarged bore 19 in the front end of the carrier 18, fitting freely therein, but just closely enough to prevent being dislodged by gravity if the gun is pointed downward.

At the front end of the barrel a cylindrical buffer 21 is secured by the transverse pin 8. The rear end of the buffer 21 has an enlarged bore formed therein in which a compression spring 25 32 is secured by any suitable means around the barrel.

A trigger guard 2 may be attached to the barrel by set screws 3 or other suitable means.

As an alternate form, a tubular slide 22 is slidably mounted in the barrel with a trigger 23 united thereto which extends downwardly through a slot 24 formed in the extension 1—a of the stock. An upward projection or lug 32—1 is formed on the lower side at the rear end of the slide 22 and when constructed in this form, the drawbar 13 has its rear 25 extended obliquely upwardly in position to contact a transverse pin 24—1 secured in the rear end of the barrel by which the drawbar will be released from the lug 32—1 or detained at the rear of the slide 22. When arranged in this form, the rear end of the drawbar is arranged to slope downwardly enough to have a downturned portion near the rear end thereof to engage the lug or detent 32—1, the front end of the drawbar being connected to the spring 14 and to the carrier 18 as in the other form.

In the operation of my gun, the parts are assembled as shown in the drawing and the barrel secured in place with the yoke 10 free to revolve in the chamber 1—1 and in the barrel.

As the crank 12 is turned, the yoke will engage the upwardly-turned projection at the rear of the drawbar 13 and carry the drawbar downwardly and to the rear, thus exerting tension

upon the spring 14. As the drawbar is carried toward its rearmost position, and after passing below the shaft 9, it moves upwardly and contacts the shaft 9 and is released from the yoke 10, which continues its upward movement. The tension of the spring 14 then carries the drawbar forward and with it the carrier 18 which in turn carries the tubular slide 20 and throws it forward forcibly so as to strike the spring 32 by which the slide 20 is bounced back into the bore 19 of the carrier 18 as the operation is repeated.

This operation may be repeated with considerable rapidity by rapidly turning the crank 12.

In the alternate form, the trigger 23 is pushed forward manually until the lug 32-1 has engaged the projection at the rear of the drawbar 13. The trigger 23 is then drawn to the rear carrying the drawbar with it until the extension 25 strikes the pin 24-1 which raises the rear end of the drawbar and releases it from the lug 32-1 and this operation may be repeated indefinitely.

The slide 20 is preferably painted with some bright color such as orange or red to simulate a flame.

Various modifications may be made in the form, proportions and arrangements of the parts without departing from the spirit of my invention and I do not limit my claims to the precise forms shown in the drawings.

I claim:

1. In a toy gun, a stock with a barrel mounted thereon, opposite longitudinal slots formed in the barrel, a drawbar slidably mounted within the barrel with a transverse pin united thereto extending outwardly through the opposed slots and with the outer ends of said pin united to a tubular carrier slidably mounted upon the barrel, a coiled tension spring mounted in the barrel engaging the front end of the drawbar and arranged to be tensioned as the drawbar is retracted and to forcibly draw the drawbar forwardly when the drawbar is released from the retractor, a manually operable retractor mounted in the stock and barrel arranged to engage the rear end of the drawbar and draw same rearwardly to a predetermined limit at which the drawbar will be released from the retractor, a tubular slide having one end arranged to seat in an enlarged bore formed in the front end of the carrier surrounding the barrel and resilient means mounted upon the front end of the barrel arranged to be contacted by the tubular slide at the forward end of its travel and to drive the tubular slide back to its seat in the carrier at the rear of the barrel.

2. A toy gun comprising a stock with a barrel mounted thereon, opposite longitudinal slots formed in the barrel, a drawbar slidably mounted within the barrel having a transverse pin united thereto extending outwardly through the slots in the barrel, the outer ends of the pin being secured in a carrier slidably mounted upon the barrel, resilient means having one end secured within the barrel and its opposite end engaging the front end of the drawbar, arranged to be

tensioned as the drawbar is drawn rearwardly and to force the drawbar forwardly when the drawbar is released, a retractor mounted in the stock arranged to engage the rear end of the drawbar and draw same rearwardly to a predetermined limit at the end of which the drawbar will be released and driven forward by the resilient means, a tubular slide mounted upon the barrel having its rear end arranged to engage and seat in an enlarged bore formed in the front end of the carrier and to be projected forward from the carrier when the carrier reaches its limit of forward travel, and a resilient buffer mounted upon the front end of the barrel whereby the tubular slide can be stopped at the end of the barrel and driven back to the carrier.

3. In a toy gun, a stock with a barrel mounted thereon, opposite longitudinal slots formed in the barrel, a flexible drawbar slidably mounted within the barrel with a transverse pin united thereto extending outwardly through the opposed slots and with the outer ends of said pin united to a tubular carrier slidably mounted upon the barrel, a tubular slide surrounding the barrel and having its rear end arranged to seat in an enlarged bore formed in the front end of the carrier, a coiled tension spring mounted in the barrel engaging the front end of the drawbar and arranged to be tensioned as the drawbar is retracted and to forcibly draw the drawbar forwardly when the drawbar is released from a retractor, a manually operable retractor mounted in the stock and barrel arranged to engage the rear end of the drawbar and draw same rearwardly to a predetermined limit at which the drawbar will be released from the retractor, said retractor including a shaft journaled in the stock, a manually operable crank united to one end thereof, and a yoke united to the intermediate portion of the shaft arranged to revolve with the shaft and to engage at each revolution a lug united to the rear end of the drawbar and carry the drawbar rearwardly for a predetermined distance and then release same.
